FILM RECORD CARD

Milton Joseph Ruterbusch, Ridgewood, N.J., and Alfred J. Thomas, Bronx, N.Y., assignors to Eastman Kodak Company, Rochester, N.Y., a corporation of New Jersey

Filed Oct. 26, 1964, Ser. No. 82,322

Term of patent 14 years

(Cl. D59—2)

FIG. 1 is a front elevational view of a film record card showing our new design;

FIG. 2 is an edge view thereof;

FIG. 3 is an enlarged cross-sectional view taken on line 3—3 of FIG. 1;

FIG. 4 is a partial rear elevational view of the film record card of FIG. 1 showing further our new design; and

FIG. 5 is another embodiment of the design shown in FIG. 1.

We claim:

The ornamental design for a film record card, as shown and described.
